CHAIR

Fred J. Murdock, Statesville, N. C.

Application February 15, 1939, Serial No. 256,591

4 Claims. (Cl. 155—178)

This invention relates to a seat for what is commonly known as a kitchen chair. This chair comprises a pair of front posts extending to a point substantially at the level of the seat and a pair of back posts extending above this level for accommodating back pieces. The front and rear posts are secured together in a common unit by suitable rungs.

It is an object of this invention to provide a chair having form fitting refinements adapted for comfortable relaxation by the occupant, which chair is durable, economical to manufacture, and which has an appeal to the critical eye. More specifically it is an object of this invention to provide a chair seat having a double curvature therein comprising a pair of substantially parallel arcuate rungs which have secured to the upper side thereof a plurality of transversely extending arcuate slats. This assembly, comprising the rungs and slats, is adapted to be placed on the top rounds between the chair posts. By providing arcuate rungs and arcuate slats, the curvature of the seat extends in both directions and throughout the width and breadth thereof. In other words, the shape of the seat is substantially spherical at the central portion thereof.

It is a further object of this invention to provide a chair seat of the class described comprising a pair of arcuately disposed rungs having arcuately disposed slats secured thereto, said rungs having their ends fitting into the front and rear posts of the chair. This type of structure will replace the cane seat heretofore used and at the same time the arcuate rungs will replace conventional top rounds which have been used to hold the chair posts together.

Due to the high cost of hand labor for weaving cane seats in this type of chair, this seat fills a great need in enabling manufacturers to produce a low price chair to fill a demand which cannot afford to pay present prices for cane seat chairs.

Some of the objects of the invention having been stated, other objects will appear as the description proceeds when taken in connection with the accompanying drawings, in which—

Figure 1 is an isometric view of a chair embodying a preferred form of the invention;

Figure 2 is a vertical sectional view taken along the line 2—2 of Figure 1;

Figure 3 is a sectional plan view taken along the line 3—3 in Figure 1;

Figure 4 is a vertical sectional view taken along the line 4—4 in Figure 2 showing the method of securing the front arcuate rung to the chair;

Figure 5 is a vertical sectional view taken along

the line 5—5 in Figure 2 showing the method of securing the rear arcuate rung to the chair;

Figure 6 is a vertical sectional view through the central portion of the chair seat and taken along the line 6—6 in Figure 2;

Figure 7 is an isometric view of a slightly modified form of the invention;

Figure 8 is a vertical sectional view taken along the line 8—8 in Figure 7;

Figure 9 is a sectional plan view taken along the line 9—9 in Figure 7;

Figure 10 is a vertical sectional view taken along the line 10—10 in Figure 8 showing the method of securing the ends of the front arcuate rungs to the front chair posts;

Figure 11 is a vertical sectional view taken along the line 11—11 in Figure 8 showing the method of securing the ends of the rear arcuate rungs to the rear chair posts;

Figure 12 is a vertical sectional view through the central portion of the chair seat and taken along the line 12—12 in Figure 8.

Referring more specifically to the drawings, the numeral 10 denotes the front chair posts and the numeral 11 denotes the rear chair posts, said rear posts being adapted to extend upwardly at a greater distance than the front posts to form a means for supporting the chair back slat members 12. The front posts 10 are tied together by suitable rounds 14, whereas the lower portion of the rear posts 11 are secured together by suitable rounds 15. The front posts 10 and the rear posts 11 are secured to each other by suitable rounds 16. The structure thus far described is conventional in what is commonly known as a kitchen chair and it is upon this framework that my invention is adapted to be placed.

In order to provide an economical yet an attractive seat for this type of a chair, which also has the maximum comfort for the occupant a seat with a double curvature therein is provided. This seat comprises a front arcuate rung 18 and a rear arcuate rung 19, which rungs have disposed transversely thereof a plurality of arcuate slats 20 by any suitable means such as nails 21 and 22. The slat members 20 are disposed in the central portion of the seat. Arcuate slats 23 are secured upon the edges or sides of the seat by any suitable means such as nails 24. These slats are very similar to the slats 20 previously described, except they are flared slightly at the front edge in order to cover up the top of the front chair posts 10.

The front ends of the slats 20 are cut to form a slightly reverse curved portion 20a, and a

50

55

similar reversed curved portion 28b is cut on the rear ends. The purpose of cutting the slats in this manner is to provide a comfortable contour of the seat as well as to provide a seat 5 which has a pleasing external appearance. The slats 23 have similar reversed down-turned curved portions 28a integral with the front ends and the rear ends of these slats are cut as at 28b to fit the rear chair posts 11. By referring 10 to Figure 2 it is seen that the upper central portion of the slats 20 and 23 are concave whereas the end portion of these slats are convex.

With the slats properly secured to the arcuate members 18 and 19, the seat is ready to be installed 15 in an ordinary kitchen chair. In order to do this, it is only necessary to place the seat upon the chair frame in the manner shown in Figure 2 after which suitable screws or nails 20 25 and 26 are used to penetrate the uppermost rungs 14 and 15 and the ends of these screws or nails are adapted to be embedded in the central portion of the arcuate rungs 18 and 19. It is thus seen that the seat of this type may be 25 easily installed upon old chair frames by merely 30 using a pair of attaching screws or nails such as designated by reference characters 25 and 26. It will be noted, however that the ends of the arcuate rungs 18 and 19 are supported by the uppermost side rounds 16 which are disposed 35 between the front and rear posts. Since the rear ends of side arcuate slats 23 have cut-away ends which encircle a part of the periphery of the chair posts 11, the seat will cover the entire top side of the chair, including the front posts 10, front rungs 14, side rungs 16 and rear rungs 15.

Figures 7 to 12, inclusive, show a slightly modified form of the invention. In this form a chair frame is shown comprising front posts 30 and 40 rear posts 31. The rear posts are adapted to extend slightly above the seat level and have disposed between their upper ends suitable arcuate slat members 32 for supporting the back of the occupant. The lower ends of front posts 30 45 are secured to each other by means of suitable rounds 33 and the lower ends of the rear posts 31 are secured together by means of a round 34. The front posts and the rear posts are secured together by suitable side rounds 35. In order 50 to provide a suitable seat for this type of chair, a front arcuate rung 36 is provided, which rung has rounded end portions 36a penetrating suitable bores near the top of front posts 30. A rear arcuate rung 37 is also provided which likewise 55 has rounded end portions 37a for penetrating suitable holes in the rear posts 31. Disposed transversely of these arcuate rungs 36 and 37 are arcuate slats 38 by any suitable means such as 60 nails 39 and 40. These slats are slightly wider at their front ends than at their rear ends so as to allow the front side of the chair seat to be slightly wider than the rear side. Each of the slats 38 has a front reverse curved portion 38a which turns downwardly immediately after 65 passing over the front rung 36. Also the rear ends of the slats 38 have a reversed curved down-turned portion 38b integral therewith which likewise turns slightly downwardly after passing over the rear arcuate rung 37. This assembly, 70 comprising the arcuate rungs 36 and 37 and the transversely disposed slats 38, forms a seat having a concave spherical surface in the central portion thereof with down-turned portions near

the front and the rear side so as to form a chair with a pleasing appearance and one that will provide maximum comfort and not chafe the legs of the occupant. It should be noted that when this type of chair seat is used the front and rear top rounds on the ordinary kitchen chair may be dispensed with and have the arcuate supporting rungs 36 and 37 substituted therefor.

In the drawings and specification there has 10 been set forth preferred embodiments of the invention, and although specific terms are employed, they are used in a generic and descriptive sense only, and not for purposes of limitation, the scope of the invention being set forth in the 15 appended claims.

I claim:

1. A chair comprising a pair of front posts, a pair of rear posts extending a substantial distance above the upper ends of the tops of the 20 front posts, a plurality of parallel rounds joining all of the posts together to make the chair framework, an arcuate rung extending between the upper ends of the front posts, a second arcuate rung extending between the rear posts at 25 substantially the same level as the first-named rung, a plurality of arcuate slats, the two rungs having their concave sides disposed upwardly, the convex side of the slats being secured near their ends to the concave sides of the arcuate 30 rungs, and the front ends of the slats being reversely curved to form a convex upper front surface on the slats.

2. A chair comprising a pair of front posts, a pair of rear posts extending a substantial 35 distance above the upper ends of the tops of the front posts, a plurality of parallel rounds joining all of the posts together to make the chair framework, an arcuate rung extending between the upper ends of the front posts, a second arcuate rung extending between the rear posts at substantially the same level as the first-named rung, a plurality of arcuate slats, the two 40 rungs having their concave sides disposed upwardly, the convex side of the slats being secured near their ends to the concave sides of the arcuate rungs, and the front and rear ends of the slats being reversely curved to form convex 45 upper surfaces on the ends of the slats.

3. A chair having a pair of front posts and 50 a pair of rear posts, a seat member supported by the posts and comprising a pair of arcuate members disposed transversely of the chair and having their concave surfaces disposed upwardly, a plurality of arcuate slats having their convex 55 sides secured to the concave upper surfaces of the arcuate members to form a seat having an upper surface which is concave in both transverse and longitudinal section.

4. A chair comprising a pair of front posts and a pair of rear posts, a plurality of rounds disposed one above the other and extending between the posts for securing the posts together, a seat member comprising a pair of arcuate members having upper concave surfaces, a plurality of arcuate slats having their lower convex surfaces secured to the upper concave surfaces of the arcuate members, and means for securing the central portions of the arcuate members to the upper front and rear rounds of the 70 chair.

FRED J. MURDOCK.
